UNITED STATES PATENT OFFICE.

GEORGE H. SMITH, OF WEBSTER, WEST VIRGINIA.

IMPROVEMENT IN DOOR-CHECKS.

Specification forming part of Letters Patent No. 221,873, dated November 18, 1879; application filed September 6, 1879.

To all whom it may concern:

Be it known that I, GEO. H. SMITH, of Webster, in the county of Taylor and State of West Virginia, have invented certain new and useful Improvements in Door-Checks; and I do hereby declare that the following is a full, clear, and exact description thereof, reference being had to the accompanying drawings, and to the letters of reference marked thereon, which form part of this specification, in which—

Figure 1 is a perspective view of my door-check, and Fig. 2 a side elevation of the same.

The object of my invention is to provide a simple and inexpensive device by which doors may be held open at any point desired; and it consists in the employment of two pieces of metal, arranged and constructed as will be hereinafter more fully set forth.

In order to enable others skilled in the art to which my invention appertains to make and use the same, I will now proceed to describe its construction and arrangement.

A represents a short steel bar, one end of which is secured to the floor at the point at which it is desired to hold the door, as shown. The opposite end of this bar is made thinner, and forms a spring, the upper surface of which is cut away to form a step, *a*, and is held up against the under surface of the door by means of an adjustable screw-bearing, *b*, by which it may be raised or lowered to suit the different doors. The extreme upper end of this bar A, beyond the step *a*, is also provided with a series of holes, *c c*.

B is another metal bar, one end of which is secured to the floor in such position that it will be at right angles, or nearly so, to the bar A. The opposite end of the bar B rests upon the upper end of the spring-bar A, and

is provided on its under side with a pin or projection, *d*, which passes through one of the holes *c*, (according to the thickness of the door,) and retains the end of the bar B in position.

The bar A having been secured at right angles to the position of the door, when open, the door is swung back, and sliding over the bar A the outer end of this bar is depressed, and the door passing over the step *a*, the bar springs up into its position again, holding the door between the step or shoulder *a* and the end of the bar B.

When it is desired to shut the door, the foot is pressed upon the bar B, and the door, being thus released, can be closed.

If desired, the surface of the door sliding upon the spring may be bound or covered with sheet metal to prevent wear.

Having thus fully described my invention, what I claim, and desire to secure by Letters Patent, is—

1. The combination of the spring-bar A, having the screw-bearing *b*, with the stop-bar B, substantially as and for the purpose set forth.

2. The within-described device for holding doors open, consisting of the spring-bar A, provided with an adjusting-fulcrum, *b*, step *a*, and holes *c c*, combined with the stop-bar B, provided with spur *d*, all constructed and arranged to operate substantially as and for the purpose described.

In testimony that I claim the foregoing as my own I affix my signature in presence of two witnesses.

GEORGE HENRISON SMITH.
